UNITED STATES PATENT OFFICE.

SIGMUND SCHLESINGER, OF NEW YORK, N. Y.

UMBRELLA.

1,247,159.

Specification of Letters Patent. Patented Nov. 20, 1917.

Application filed January 27, 1917. Serial No. 144,805.

To all whom it may concern:

Be it known that I, SIGMUND SCHLESINGER, a citizen of the United States, and resident of New York city, borough of Manhattan, in the county of New York and State of New York, have invented certain new and useful Improvements in Umbrellas, of which the following is a specification.

The object of my invention is to provide simple and efficient means for retaining an umbrella closed and a tip cup thereof in co-operation with the tips of the ribs, so arranged that when the retaining means are operated to release the runner the tip cup will be automatically released from the tips to permit the umbrella to be opened or to automatically open when it is provided with springs for opening it.

My invention comprises novel details of improvement and combinations of parts that will be more fully hereinafter set forth and then pointed out in the claims.

Reference is to be had to the accompanying drawings forming part hereof, wherein, Figure 1 is a side view of an umbrella embodying my invention, shown in the closed position with the tips of the ribs retained in the tip cup;

Fig. 2 is an enlarged detail sectional view illustrating parts of the umbrella in an opened position;

Fig. 3 is an enlarged detail sectional view illustrating parts of the umbrella in the closed position and the tips of the ribs retained by the tip cup;

Fig. 4 is a similar view illustrating the parts they assume when the tip cup is released from the tips with the runner retained in the position shown in Fig. 3, and

Fig. 5 is an enlarged detail section illustrating the runner and tip cup keeper fully operated.

The numeral 1 indicates a tubular umbrella rod of any ordinary type, to which the ribs 2 are pivoted at 3, the braces 4 being pivoted to the ribs at 5 and at 6 to a runner 7 in any suitable manner. The runner 7 is shown provided with a fitting 8 to which the braces 4 are pivoted at 6 and to which springs 9 are connected at 10, the springs being also connected with the ribs for causing automatic opening of the umbrella in a wellknown manner. Fitting 8 is adapted to engage a stop 11 on rod 1 to limit the opening of the umbrella. At 12 is a tip cup

or tip retainer shown in hollow or open-ended form to receive the tips of the ribs 2 and having a tubular portion at 13, which, in the example illustrated, are slidably mounted upon the runner 7 between the fitting 8 and a stop or shoulder 14 at the outer end of the runner. A coiled spring at 15 surrounds the runner and is adapted to bear against the tip cup to move it toward the umbrella handle, said spring bearing also against the fitting 8. I have shown the tip cup or retainer 12 provided with a tubular extension 16 (on the side opposite the tubular portion 13) that surrounds the spring 15, and at 17 is a sleeve entering tubular extension 16 and surrounding spring 15, said sleeve 17 being shown provided with an inner flange or shoulder 18 slidable on runner 7 and serving as a stop for the end of spring 15, which pushes the sleeve 17 against fitting 8. The extension 16 and sleeve 17 telescope and the latter serves to guide the former while they both inclose and hide the spring. The tendency of spring 15 under expansion is to move the tip cup or retainer away from the rib tips to the position shown in Fig. 4 to release the tips, the tubular portion 13 of the tip cup then abutting against the stop 14 on the runner to limit the outward movement of the tip cup. Means are provided to retain the runner in the closed position as well as to retain the tip cup or retainer with the rib tips therein (Figs. 1 and 3), and whereby the tip cup may be released to move away from the rib tips and the runner may also be released to open the umbrella. For such purpose I have shown a keeper 19, shown in the form of a projection or finger carried by a resilient or spring-acting member 20, that is shown pivoted at 21 within tubular rod 1, the latter being shown provided with a slot 22 for the passage of projection 19. Member 20 is also provided with a finger piece 23 operative in slot 22 and normally projecting through tubular rod 1, the member 20 bearing against the rod to bend when the finger piece is pushed inwardly.

The arrangements described are such that to close the umbrella one may grasp the tip cup or retainer 12 and draw down the runner, the braces and the ribs in an ordinary manner, the tip cup sliding on the runner to the stop 14. When the runner is in the closed position the keeper 19 will pass through a

slot 24 in the runner to retain the umbrella closed, at which time tubular portion 13 of the tip cup will be over keeper 19, as illustrated in Fig. 4. The tip cup then will be 5 in such position as to enable the rib tips to be folded together to receive the tip cup, which then may be manually pushed along the runner against the tension of spring 15 to receive the tips, as in Fig. 3, whereupon 10 the keeper 19 will be caused, by the resilient member 20, to pass farther outwardly through slot 24 in position to oppose the outer end of tubular portion 13 of the tip cup to retain the latter around the tips of 15 the ribs. The umbrella will then be retained closed, since keeper 19 retains at the same time the runner and the tip cup as shown in Fig. 3. When it is desired to open the umbrella it is merely necessary to push 20 the finger piece 23 inwardly and as keeper 19 passes from the position opposing the end of tubular portions 13, the spring 15 will push the tip cup outwardly toward the handle to release the rib tips, and the continued movement of keeper 19 will cause it 25 to pass out of slot 24 and runner 7 to release the latter (Fig. 5), whereupon the springs 9 will cause automatic opening of the umbrella. If springs are not used for the latter purpose, the user may push the runner 30 to an open position in an ordinary manner, and the runner may be retained by the usual stop on the umbrella rod.

I have shown the edge of keeper 19 beveled or inclined at 19^a (Fig. 3) to permit the outer end of the tubular portion 13 of the tip cup to slide over said keeper when the umbrella is being closed by pushing upon the finger piece 23, whereby the keeper will 35 assume the position shown in Fig. 4 and will retain runner 7 in the closed position. The keeper 19 is also shown provided with a notched portion at 19^b to coact with the edge of tubular portion 13 of the tip cup 40 to serve in retaining the latter in the tip-holding position shown in Fig. 3 against the tension of spring 15, so that such spring will not tend to slide the tubular portion 13 over keeper 19, when the parts are in such 45 position, whereby the tip cup will be retained on the tips to prevent spontaneous opening of the umbrella, requiring manual 50

operation of the keeper to permit opening of the umbrella.

Having now described my invention what 55 I claim is:—

1. In an umbrella, the combination of a rod and ribs pivotally connected therewith, with a runner connected with the ribs, a tip cup slideable relatively to the rod, and provided with a tubular portion slideable on the runner to move therewith, said runner having a slot over which the tubular portion of the tip cup may pass, and a keeper carried by the rod adapted to pass through 60 said slot to retain the runner in a closed position and to oppose the tubular portion of the tip cup to retain the latter in coaction with the rib tips. 65

2. In an umbrella, the combination of a rod and ribs pivotally connected therewith, with a runner connected with the ribs, a tip cup slideable relatively to the rod, and provided with a tubular portion slideable on the runner to move therewith, said runner having a slot over which the tubular portion of the tip cup may pass, and a keeper carried by the rod adapted to pass through 70 said slot to retain the runner in a closed position and to oppose the tubular portion of the tip cup to retain the latter in coaction with the rib tips, said keeper having a notched portion 75 for engagement with the tubular projection of the tip cup whereby said portion will be opposed by the keeper to prevent the tip cup from releasing the rib tips. 80

3. In an umbrella, the combination of a rod and ribs pivotally connected therewith, with a runner connected with the ribs, a tip cup slideable upon the runner, a spring surrounding the runner, and coactive with a stop thereon and with the tip cup to move the latter from the rib tips, and a keeper adapted to pass through a slot in the runner 90 to retain the latter in closed position and to coact with the tip cup to retain the latter in coaction with the rib tips. 95

Signed at New York city, in the county of New York and State of New York, this 26th day of January, A. D. 1917.

SIGMUND SCHLESINGER.
